GAME BOARD

Gilbert O. Thibault, 4 Loring Ave., Salem, Mass.

Filed Apr. 23, 1963, Ser. No. 74,591

Term of patent 14 years

(Cl. D34—5)

The figure is a plan view of a game board showing my new design, the characteristic features of which reside in the combination on the game board disclosed of the particular decorated pathways and borders, all as shown. The board itself is of conventional thickness and the rear side of the board, not shown in the drawing, has a plane surface.

I claim:

The ornamental design for a game board, substantially as herein shown and described.
